(57) **CLAIM**

The ornamental design for a work lamp, as shown and described.

DESCRIPTION

FIG. 1 is a left, front, top perspective view of a work lamp showing my new design;

FIG. 2 is a right, rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

In the drawings, the broken lines depict portions of the work lamp that form no part of the claimed design.

The claim is directed to shaded surfaces. The broken lines immediately adjacent the shaded areas represent the bounds of the claimed design while all other broken lines are directed to portions of the work lamp that form no part of the claimed design; the broken lines form no part of the claimed design.
